UNITED STATES PATENT OFFICE.

HENRI MAISCH-BITSCHENAUER, OF PARIS, FRANCE, ASSIGNOR TO CHENEY BROTHERS,
OF SOUTH MANCHESTER, CONNECTICUT, A CORPORATION OF CONNECTICUT.

DESIGN FOR TEXTILE FABRIC.

44,688.

Specification for Design.

Patented Sept. 23, 1913.

Application filed August 13, 1913. Serial No. 784,510. Term of patent 3½ years.

To all whom it may concern:

Be it known that I, HENRI MAISCH-BITSCHENAUER, a citizen of France, residing at Paris, France, have invented a new, original and ornamental Design for Textile Fabrics, of which the following is a specification, reference being had to the accompanying drawing, forming a part thereof.

The single figure of the drawing is a

plan view of a portion of a textile fabric illustrating my new design.

I claim:

The ornamental design for a textile fabric, as shown.

HENRI MAISCH-BITSCHENAUER.

Witnesses:

SENILE BITSCHENAUER,
AL JENCKER.
